G. H. BOLUS.
SECTION INSULATOR.
APPLICATION FILED DEC. 20, 1917.

1,285,006.

Patented Nov. 19, 1918.

UNITED STATES PATENT OFFICE.

GLENN HENRY BOLUS, OF MANSFIELD, OHIO, ASSIGNOR TO THE OHIO BRASS COMPANY,
OF MANSFIELD, OHIO, A CORPORATION OF NEW JERSEY.

SECTION-INSULATOR.

1,285,006.

Specification of Letters Patent. Patented Nov. 19, 1918.

Application filed December 20, 1917. Serial No. 207,993.

To all whom it may concern:

Be it known that I, GLENN H. BOLUS, a citizen of the United States, residing at Mansfield, in the county of Richland and 5 State of Ohio, have invented certain new and useful Improvements in Section-Insulators, of which the following is a specification.

This invention relates to section insulators 10 of the type used for dividing the overhead conductor or trolley wire of an electric railway into sections and insulating the sections one from the other and comprising means for connecting the sections so as to make 15 them electrically continuous or to disconnect said sections one from the other for the purpose of controlling the current in the electric circuit.

One object of this invention is to provide 20 an improved device of the character referred to which will be strong, durable and simple in construction, effective and efficient in operation and which may be readily and conveniently installed into or removed from 25 operative position.

Another object of the invention is to produce 30 a section insulator provided with means for electrically connecting or disconnecting the adjacent ends of two conductors with- out varying the tension of the conductors and comprising means for yieldingly maintaining said connecting means in or out of 35 electrical engagement with said conductor ends.

A further object of the invention is the 40 provision of a device of this character wherein in the constructional arrangement of the various parts is such as not to form an obstruction in the path of or to interfere with the traveling collector of cars when the device is engaged for disconnecting the sections.

A still further object of the invention is to 45 provide a section insulator having an insulation member provided with a plurality of sides rotatably mounted intermediate the adjacent ends of the conductors thereby rendering the overhead construction more nearly continuous and eliminating the gaps 50 or "breaks" in the system for the traveling collector to encounter.

To the attainment of these ends and the accomplishment of other new and useful objects, as will appear, the invention consists 55 in the features of novelty in the construction,

combination and arrangement of the several parts hereinafter more fully described and claimed and shown in the accompanying drawings illustrating the embodiment of the invention, and in which—

Figure 1 is a side elevational view of a section insulator constructed in accordance with the principles of my invention, a portion of the connecting bar being removed in order to illustrate the constructional arrangement of the various parts.

Fig. 2 is an end view of the device.

Fig. 3 is a plan view of the device showing the end members as electrically connecting by the switch blade.

Fig. 4 is a similar view as Fig. 1 and illustrating the handle for actuating the switch blade and the means for yieldingly maintaining the same in either closed or open position, and showing also the lower portions of two insulators or supports to which the device is shown as being attached.

Fig. 5 is a view partly in section, taken on the line 5—5 of Fig. 1, illustrating the manner in which the insulation block is 80 mounted.

Fig. 6 is a plan view of the mechanism for readily and conveniently securing the device to insulated supports or the like.

Referring to the drawings in which like 85 reference characters indicate the same parts in the different views, (1) and (2) designate metallic end members provided with sockets (3) and (4) adapted to receive the ends of the insulation connecting bars (5) and (6) 90 which are rigidly secured therein. The end members are formed with projections (7) and (8) having laterally extending arms (9) and (10) slotted to receive the contact members (11) and (12), the purpose of 95 which will be described hereinafter. The projections (7) and (8) extend toward and are in alinement with each other, their lower surfaces being adapted to be engaged by the trolley wheel when the latter passes thereunder. Sockets (13) and (14) are provided in the exterior ends of and in alinement with the projections (7) and (8) and adapted to receive the respective ends of the conductors (15) and (16), which may be secured there- 100 in any suitable or desirable manner. A shaft (17) is rotatably mounted in suitable bearings provided in the insulation connecting bars (5) and (6), and carries a supporting member (18) provided with a flange 105

110

(19), to which a switch blade (20) is secured by the bolts (21). The switch blade (20) is mounted in alinement with and adapted by rotation to engage or disengage 5 the contact members (11) and (12) thereby to electrically connect or disconnect the end members to which the electrical conductors are secured. The supporting member (18) is provided also with a pocket (22) located 10 in line with and intermediate the ends of the projections (7) and (8), and which is adapted to receive and hold an insulation member (23), provided with a suitable aperture through which the shaft (17) passes. When 15 the switch blade (20) is engaged for electrically connecting the conductors (15) and (16), the pocket (22) is adapted to be positioned intermediate the projections (7) and (8), the end of the pocket providing a metallic surface on one side of the insulation member (23) for engagement with the trolley wheel, as shown in Figs. 1 and 3 of the drawings.

The parts above referred to may be 25 assembled by first arranging the insulator connecting bars (5) and (6) within the sockets (3) and (4) of the metallic end members (1) and (2), and then securing the parts together by means of the bolts as shown or 30 otherwise. The supporting member (18) having the switch blade (20) secured thereto and the insulation member (23) positioned in the pocket (22) thereof is then arranged in position between the bars (5) and (6) 35 and the shaft (17) inserted. The shaft and the supporting member (18) may then be interlocked against relative rotation by inserting the pins as shown, or by any other suitable means.

40 A handle (24) for actuating the shaft (17) is provided and has one end of a tension spring (25) connected thereto as indicated at (26), the other end of the spring being connected to a bracket (27), provided 45 with ears (28), having threaded apertures adapted to receive adjusting screws (29), the ends of which are adapted to engage and thereby limit the movement of the handle (24), which is yieldingly maintained 50 in contact therewith by the spring (25) when moved in either direction for the purpose of preventing the accidental opening or closing of the switch.

55 For the purpose of readily and conveniently attaching the device to a support, an internally threaded sleeve (30) provided with a polygonal flange (31) is rotatably mounted upon a yoke (32) provided at each end of the device. The yokes (32) are preferably secured to the end members (1) and (2) and are each provided with an aperture adapted to loosely receive a bolt (33) which engages the sleeve (30) and is interlocked against relative rotation therewith. 60 99 An adjusting collar (34) having a polygonal

opening adapted to receive and engage the flange (31) for rotating the sleeve (30), surrounds the latter. The adjusting collar (34) is provided with a limited vertical movement and the exterior surface thereof is preferably formed for engagement with a wrench, and is adapted, when the device is secured to a support, to be clamped between the lower surface of the support and the top surface of the yoke, thereby effecting a rigid 75 connection of the parts.

Having fully described my invention and illustrated the embodiment of the same, I do not wish to be limited to the details of the construction shown, since these can be 80 obviously changed without departing from the spirit and scope of the invention.

I claim as my invention:—

1. In mechanism of the character described, the combination of a pair of end 85 members each comprising a projection which extends toward and in alinement with the other, a pair of nonconducting bars connecting the end members, an insulation member rotatably mounted intermediate the end 90 members and in alinement with the projections, a fulcrumed switch blade between the nonconducting bars and in spaced relation with the insulation member and interlocked therewith against relative rotation adapted 95 to co-act with the end members thereby to electrically connect or disconnect them, and means for actuating the switch blade.

2. In mechanism of the character described, the combination of a pair of end 100 members comprising projections extending toward and in alinement with each other, parallel nonconducting bars connecting the end members, an insulation member having 105 a plurality of sides rotatably mounted intermediate the end members and in alinement with the projections, a fulcrumed switch blade between the nonconducting bars and in spaced relation with the insulation member and interlocked therewith against relative rotation adapted by manipulation to engage or disengage the end members thereby 110 to electrically connect or disconnect them, a handle for manipulating the switch blade, and means for attaching the device to a 115 support.

3. In mechanism of the character described, the combination of a pair of end members, nonconducting bars connecting the end members, an insulation member having 120 a plurality of sides rotatably mounted intermediate the end members, a metallic cover on one of the sides of the latter, a fulcrumed switch blade mounted between the bars in spaced relation with the insulation member and interlocked therewith and in approximately parallel relation with the metallic covered side thereof adapted to be rocked into and out of contactual engagement with the end members, means for rocking the 125 130

switch blade, and means engaging the rocking means for yieldingly maintaining the switch blade in or out of contactual engagement with the end members.

- 5 4. In a device of the character described, the combination of a pair of end members provided with sockets for attaching conductors thereto and having alined surfaces to engage a trolley wheel, parallel nonconducting bars connecting the end members, a shaft 55 rotatably mounted in the bars, an insulation member provided with a plurality of sides mounted on the shaft between the bars and spaced apart from the insulation member, a handle on the shaft for turning the latter 60 thereby to cause the switch blade to electrically connect or disconnect the end members, and means for attaching the device to a support.
- 10 15 5. In a device of the character described, the combination of a pair of end members provided with sockets for attaching conductors thereto, a pair of nonconducting bars connecting the members, a bearing in each 65 of the bars, an insulation member provided with a plurality of sides between the bars and intermediate the end members, a switch blade between the bars and in interlocked spaced relation with the insulation member, 70 a shaft for the switch blade and the insulation member rotatably mounted in said bearings, a handle for turning the shaft thereby to cause the switch blade to electrically connect or disconnect the end members, means 75 for limiting the movement of the handle in either direction by engagement therewith, and means for yieldingly maintaining the handle in engagement with the last mentioned means.
- 20 25 30 35 40 45 50 55 60 65 70 75 80 85 90 95 6. In a device of the character described, the combination of a pair of end members provided with alined surfaces to engage a trolley wheel and having means for attaching wires thereto, parallel nonconducting bars connecting the end members, a bearing 80 in each of the bars, a shaft rotatably mounted in the bearings, an insulation member having a plurality of sides mounted on the shaft between the bars and intermediate said alined surfaces, a metallic surface on one side of the insulation member and in alinement with said alined surfaces, a switch blade on the shaft between the bars and spaced apart from the insulation member, 85 a handle on the shaft for turning the latter thereby to cause the switch blade to electrically connect or disconnect the end members, and means for attaching the device to a support.
7. In a section insulator for electrical conductors, the combination of two end members comprising projections extending toward and in alinement with each other and insulated from each other, insulation bars connecting the members, a switch blade between the bars, a blade support rotatably mounted in the bars, an insulation member having a plurality of sides mounted on the blade support in alinement with said projections and in spaced relation with the blade, 75 a handle secured to the blade support for operating the same, and means for attaching the device to a support.
8. A section insulator embodying two end members, each provided with a projection 80 which extends toward and in alinement with the other and having their lower surfaces disposed in the same plane, a pair of nonconducting bars connecting the members, a shaft rotatably mounted in the bars, a switch 85 blade mounted on the shaft between the bars, and a handle for operating the shaft, in combination with an insulation member having a plurality of sides mounted on the shaft between the bars in alinement with 90 said projection and in spaced relation with the switch blade, a metallic surface on one side of the insulation member disposed in the same plane as the lower surfaces of said projections, stops for the handle, and means 95 for yieldingly maintaining the handle in engagement with the stops.

In testimony whereof I affix my signature.

GLENN HENRY BOLUS.
